UNITED STATES PATENT OFFICE.

LOUIS T. TROIANO, OF PORT WASHINGTON, NEW YORK.

RAIN-ALARM.

1,280,116.

Specification of Letters Patent. Patented Sept. 24, 1918.

Application filed September 5, 1917. Serial No. 189,851.

To all whom it may concern:

Be it known that I, LOUIS T. TROIANO, a citizen of the United States of America, residing at Port Washington, in the county of 5 Nassau and State of New York, have invented new and useful Improvements in Rain-Alarms, of which the following is a specification.

This invention relates to alarms or signals 10 and has particular reference to a means for informing the occupants of a building that it is raining outside.

The primary object of the invention is the provision of an electric circuit including 15 a battery, a signal and a switch installed within a building together with a means for closing the circuit, said means being placed outside of the building and provided with a pair of contacts slightly spaced apart 20 and adapted to be bridged by the adhesion of rain drops therebetween in order to warn the occupants that it is raining.

Another object of the invention is the provision of a device of the class described 25 which is simple in construction, inexpensive to manufacture and thoroughly reliable and efficient for the purpose for which it is intended.

With these and other objects in view the 30 invention resides in the novel construction, combination and arrangement of parts fully described in the specification and particularly pointed out in the appended claim.

In the drawings:

Fig. 1 is a side elevation of the circuit 35 closing means.

Fig. 2 is a transverse sectional view there- 40 through.

Fig. 3 is a diagrammatic view of the 45 circuit.

Fig. 4 is a detail fragmentary sectional 50 view.

Fig. 5 is a detail view of a slightly modi- 55 fied form of collecting means.

Referring to the drawings by numerals, 10 designates a base to which is secured the 60 upstanding supporting members 11 and 12. A collecting funnel 13, is supported by the members 11 and 12 substantially as shown.

The supporting member 12 is provided with a cross bar 14, the terminals of which are 65 passed through the member 12, adapted to receive the thumb nuts 15. Passed through

the cross bar 14, are the threaded terminals 16 of a pair of identically formed contact 55 members 17, the latter being slightly spaced apart at their inner ends and provided with cuplike portions 18. The threaded terminals 16, are insulated from the cross bar 14, by means of insulation 19, and are adapt- 60 ed to receive the nuts 20, which also serve as binding posts for the wiring 21. The wiring 21, is included in a circuit having a battery 22, a signal 23, and a switch 24.

In use of the device the switch 24, is nor- 65 mally closed and the contact members being spaced apart causes the circuit to be nor- mally open. When rain begins to fall the funnel 13 collects the rain drops which 70 gravitate into the cuplike portions 18, of the contact members and thence between the lower portions of the same which bridges the space therebetween and causes the signal 23, to inform the occupants of the building in 75 which the device is installed that rain is falling. The switch may then be opened in order to cut off the alarm.

In the modification shown in Fig. 5, the cuplike portions 18^a, are substantially en- 80 larged whereby to provide a collecting means for the rain drops thereby eliminat- 85 ing the necessity of the funnel 13.

While I have shown and described my in- 90 vention as adapted for the purpose of a rain alarm, I, however, desire it understood, that 95 I do not care to be limited to this use as the same may be adapted for many other pur- 100 poses; nor do I care to be limited to the exact details of construction but wish it under- 105 stood that such changes and alterations as fall within the scope of the appended claim may be resorted to when desired.

What I claim is:

A circuit closer for rain alarms comprising, mating terminals provided with por- 95 tions spaced relatively and adapted to be bridged by the adhesion of moisture there- 100 between, a base member, a supporting struc- 105 ture rising from said member, means for mounting the mating terminals from the supporting structure, and a rain collector carried by the supporting structure and hav- 110 ing a discharge end opening to said mating terminals.

In testimony whereof I affix my signature. 105
LOUIS T. TROIANO.
